OSCAR WILLSON, OF SPRINGFIELD, AND EDWARD F. PIWCZYNISKI, OF HOLYOKE,
MASSACHUSETTS.

VALVE-SEAT CUTTER.

1,414,060.

Specification of Letters Patent. Patented Apr. 25, 1922.

Application filed December 1, 1920. Serial No. 427,506.

To all whom it may concern:

Be it known that we, OSCAR WILLSON, of Springfield, in the county of Hampden and State of Massachusetts, and EDWARD F. PIWCZYNISKI, of Holyoke, in said county and State, both citizens of the United States of America, have invented a new and useful Valve-Seat Cutter, of which the following is a specification.

- 10 Our invention relates to improvements in manually-operated implements for cutting, recutting, or resurfacing valve-seats in internal-combustion engines, and consists essentially of a stem, spindle, or rod receivable 60
15 in the valve-stem guide of an internal-combustion engine, and adapted to be secured to such guide, a cutting element of peculiar construction mounted to rotate on said rod and adapted to act on the valve-seat associated 65
20 with said guide, and means to hold said cutting element with the cutting edges thereof in contact with such valve-seat, and to advance or move the same toward said seat as the latter is cut away or reduced by the 70
25 action of the cutting parts, so that the latter are maintained in operative position during the cutting process, together with such subsidiary and auxiliary parts and members as may be necessary or desirable in order to 75
30 render the device or implement complete in every respect, all as hereinafter set forth.

The primary object of our invention is to produce a comparatively simple and inexpensive cutter with which valve-seats may 80
35 be easily, conveniently, expeditiously, and accurately resurfaced.

A further object is to provide an implement of this character with removable blades, whereby the life of said implement is 85
40 prolonged indefinitely, and the blades can be reground and their life also considerably prolonged.

Still another object is to afford means in the cutter for advancing the cutting element 90
45 as required during the resurfacing operation.

Other objects and advantages will appear in the course of the following description.

We attain the objects and secure the advantages of our invention by the means 95
50 illustrated in the accompanying drawings, in which—

Figure 1 is a side elevation of a valve-seat cutter which embodies a practical form of our invention, said cutter being shown in 100
55 operative relation to a valve-seat and in cut-

ting position; Fig. 2, a central, vertical section through said cutter, the valve-seat members being present in section as in the first view, and, Fig. 3, a bottom plan of the holder for the blades and of the blades themselves. 60

Similar numerals refer to similar parts throughout the several views.

In the first two views we show in section a valve-seat 1 at the top of a casing 2, and a valve-stem guide 3. These or similar elements or members are present in all internal combustion engines, so that our appliance is applicable or may be made applicable to practically any engine of this type, the purpose of the appliance being to cut, recut, or resurface said valve-seat 1 or any similar valve-seat. 70

This valve-seat cutter comprises a stem, spindle, or rod 4 which is screw-threaded at 75 its upper terminal, as at 5, and at its lower terminal, as at 6, and is provided intermediate of the screw-threaded portions with an annular enlargement 7 to form a shoulder 8, a blade holder 9, a sleeve 10, and a plurality of nuts and washers, as will presently more clearly appear. The part of the rod 4 that is above the enlargement 7 is larger in diameter than that part of said rod that is below said enlargement. 80

The rod 4 is adapted to have its lower portion inserted in the valve-stem guide 3 from above as far as the shoulder 8, which is on the bottom of the enlargement 7, will permit, the latter then resting on top of 90 said guide. When the rod 4 is in place in the guide 3, with the shoulder 8 bearing on the upper edge of said guide, said rod extends some distance below the bottom edge of said guide. The rod 4 is secured to the 95 guide 3 by means of a nut 11 and a check-nut 12 on the threaded part 6 of said rod, with whatever number of washers, as 13, 14, and 15, may be needed to locate said nuts near the bottom end of the rod when said 100 nuts are tightened. Without the aforesaid washers, it would be necessary to provide a longer screw-thread on the lower terminal portion of the rod 4, and to consume very much more time in securing said rod to the guide 3 and in releasing it therefrom, unless said guide were of unusual length, or the part of the rod below the shoulder 8 were much shorter, as will readily be seen. The washers 13, 14, and 15 are of different widths or 110

lengths, and all are not required when the guide 3 is longer than in the present case. As a matter of fact, any number of washers may be provided, and they may vary in widths and lengths to whatever extent may be desired, the only requirement being, of course, to provide the necessary filling element or elements between the bottom edge of the guide 3 and the upper surface of the 10 nut 11.

The holder 9 is rigidly affixed to the base of a hollow stem or sleeve 17 which is loosely mounted on the rod 4, and said holder is equipped with four blades 18. Said holder 15 extends in opposite direction from the vertical center thereof, and in such extensions or arms are four slots 19 to receive the blades 18, there being two such slots in each of said arms. The slots 19 in opposite pairs are in 20 offset relationship, so as to locate the blades 18 out of line with each other and thus prevent chattering. Each pair of blades 18 is held in place by means of a taper pin 20, which pin passes through one arm of the 25 holder 9, and through said blades, transversely. Upon removing the pins 20, the blades 18 can be taken from the holder 9 for the purpose of being reground, or in order that they may be replaced with others. 30 The blades 18 have oblique cutting edges, the angle of which corresponds with that of the valve-seat 1. The sleeve 17 has flattened parts on opposite sides thereof, one such part appearing at 21 in Fig. 1, for the application of a wrench or other tool or implement by means of which said sleeve and the holder 9 with its blades 8 are rotated during the cutting operation.

The sleeve 10 has a longitudinal slot 22 40 therein, into which slot a pin 23 projects from the rod 4. Thus the sleeve 10 is permitted a limited amount of longitudinal movement, but held against rotation on the rod 4.

45 One or more washers, as 24 and 25, are placed on the rod 4 between adjacent ends of the sleeves 17 and 10, and there is a nut 26 on the screw-threaded portion 5 of said rod above said sleeve 10.

50 The washers 24 and 25 are for similar purposes as are the washers 13, 14, and 15, that is to say, they are space fillers between the sleeves 17 and 10, and may vary in number and thickness or length, as in the other case, such factors being governed by the distance from the horizontal plane of the valve-seat 1 to the bottom of the sleeve 10, when said sleeve is raised on the rod 4 as far as the pin 23 will permit, or, in any event, 55 located with the top of the slot 22 some distance above said pin.

If all valve-seat casings and valve-stem guides were of the same length, respectively and relatively, our appliance could be constructed so that it would not be necessary to

provide any space-filling members at its ends, but such not being the case, and inasmuch as it is desired to construct said appliance so that it is applicable to a great variety of valve-seat members, the appliance 70 is made long enough to accommodate valve-seat casings and valve-stem guides of maximum lengths, and adapted to such members when under or less than the maximum, as we have shown, provided the washers of 75 which mention has been made, either the identical washers shown in the drawings or others, according to the requirements in any other given example, be furnished and used.

In practice, assuming that the blades 18 80 be in place in the holder 9, the application and operation of the valve-seat cutter is described as follows:

While the rod 4 is denuded of the nuts and washers at the bottom, said rod is introduced into the top of the valve-stem guide 3 and passed downwardly through said guide until the shoulder 8 comes to rest on the top of the guide. Next the washers 13, 14, and 15, are slipped up onto the rod 4 from below, and the nut 11 is screwed on to said rod beneath said washers and tightened thereon until the guide 3 is gripped tightly between the shoulder 8 and the washer 13, so that said rod is held securely in place in said 95 guide. Then the check-nut 12 is screwed on to the terminal 6 of the rod 4 against the under side of the nut 11.

While the nut 26 and the sleeve 10 are off of the rod 4, it first being necessary to remove the pin 23 before said sleeve can be removed from said rod, the sleeve 17 is passed on over the top of the rod and downwardly thereon until the cutting edges of the blades 18 come to rest on the valve-seat 1. 100 The washers 25 and 24 are then placed on the rod 4 on top of the holder sleeve 17, and the sleeve 10 is placed on said rod over said last-named washer and there secured, within the range of movement permitted by the 110 slot 22, by means of the pin 23 which is replaced in the rod. Finally the nut 26 is screwed on to the threaded terminal 5 of the rod 4.

A suitable instrument, as a wrench, is now 115 applied to the sleeve 17 and said sleeve with the holder 9 and the blades 18 is rotated, with the result that the valve-seat 1 is cut away by said blades. As the valve-seat 1 is cut away the nut 26 is screwed down to 120 force downwardly the sleeve 10, the washers 24 and 25, and the sleeve 17 with the holder and blades, and retain the latter in contact with the valve-seat 1. These operations are continued until the valve-seat is 125 resurfaced to the required extent. The nut 26 causes the blades 18 to bear forcibly on the valve-seat 1 in the first instance, and as said nut is screwed downwardly the forcible engagement of said blades with said seat 130

is maintained throughout the resurfacing operation. The vertical movement of the parts during the resurfacing operations is, of course, comparatively slight, and ample provision is made for the same by the slot 22. The sleeve 17 is free to revolve on the spindle under a force sufficient to overcome the frictional resistance offered thereto by the sleeve 10 and the valve-seat 1, when 10 said sleeve 10 is forcibly contacted with by the nut 26, and the same is true of the washers 24 and 25.

After the valve-seat 1 has been cut, the check-nut 12 and the nut 11 are unscrewed 15 from the terminal 6, the washers above said nut are removed from the rod 4, and the latter is withdrawn in an upwardly direction from the guide 3 without removing the parts carried by said rod above the enlargement 7, unless it should be desired first to remove them.

It is not necessary to remove the parts which are carried by the rod 4 above the enlargement 7, except for the purpose of introducing washers between the sleeves 10 and 25 17, the aggregate length or width of which is greater or less than of that of the two washers used in the present example.

It is required that the holder 9 be located 30 a sufficient distance above the enlargement 7, when the appliance is in operative position, to enable the cutting parts to move downwardly on the rod 4 to the extent required for the proper cutting of the valve-seat, consequently the part or parts above the sleeve 17 must be proportioned with such end in view.

When the blades 18 become dull, or if for any reason it is desired to take said blades 40 from the holder 9, it is a very simple matter to drive out the pins 20 and remove the blades from said holder, so that the blades can be sharpened, or replaced with others; and it is an equally simple matter to return 45 the resharpended or supply new blades to the holder and resecure them with said pins. In many, not to say most, cases, the blades can, if preferred, be sharpened without removing them from the holder.

50 More or less change in the size, shape, construction, and arrangement of some or all of the parts of this appliance may be made without departing from the spirit of our invention or exceeding the scope of what is claimed.

What we claim by our invention, and desire to secure by Letters Patent, is—

1. The combination, in a valve-seat cutter, with a rod receivable in a valve-stem

guide, and having an integral shouldered 60 part to bear on such guide, and means on said rod to engage the bottom of said guide and cooperate with said shouldered part to secure said rod to the guide, of a shouldered sleeve arranged to slide and rotate on said 65 rod above the shouldered part thereof, cutting means mounted on and fixed to said sleeve below the shoulder thereon, and means on said rod to retain said cutting means in engagement with a valve-seat. 70

2. The combination, in a valve-seat cutter, with a rod receivable in a valve-stem guide, and having an integral shouldered part to bear on said guide, and means on said rod to bear against the bottom of said 75 guide and cooperated with said shouldered part to secure the rod to the guide, of a shouldered sleeve mounted to slide and rotate on said rod above said shouldered part, cutting members mounted on and fixed to 80 said sleeve below the shoulder thereon, and means on said rod to force said sleeve and cutting members toward a valve-seat.

3. The combination, in a valve-seat cutter, with a rod receivable in a valve-stem 85 guide, and having a shouldered part to bear on said guide, and engaging means on said rod for the bottom of such guide, which engaging means cooperates with said shouldered part to secure the rod to the guide, of 90 cutting members mounted to rotate on the rod above said shouldered part, and means to actuate said cutting members toward a valve-seat, said last-named means consisting in part of a slotted sleeve on the rod, and 95 of a nut threaded to said rod above said sleeve, the rod having a pin extending into the slot in said sleeve.

4. The combination, in a valve-seat cutter, with a rod receivable in a valve-stem guide, and having a shouldered part to bear on said 100 guide, and means on said rod to bear on the bottom of said guide and cooperate with said shouldered part to secure said rod to the guide, of a sleeve mounted to slide and rotate on the rod above said shouldered part, and provided with a holder which is affixed thereto, blades carried by said holder, and means to retain said blades in contact with the valve-seat as they cut away the surface 105 of the same.

OSCAR ^{his} WILLSON.
